BOWLING LANE MULTIPLE SEATING UNIT

Thomas A. Meade, Huntington, N.Y., assignor to
AMF Incorporated, White Plains, N.Y.

Filed Jan. 24, 1974, Ser. No. 436,058

Term of patent 14 years

Int. Cl. D6—06

U.S. Cl. D6—197

FIG. 1

FIG. 2

FIG. 1 is a perspective view of a bowling lane multiple seating unit of my design; and

FIG. 2 is another broken away perspective view.

The rear of the seats not shown are the same in appearance as the seats shown.

I claim:

The ornamental design for a bowling lane multiple seating unit, as shown and described.
